UNITED STATES PATENT OFFICE.

FLORENCE F. CONNER, OF CLEVELAND, OHIO.

DESIGN FOR A PAD-HOOK.

SPECIFICATION forming part of Design No. 26,835, dated March 30, 1897.

Application filed February 16, 1897. Serial No. 623,743. Term of patent 14 years.

To all whom it may concern:

Be it known that I, FLORENCE F. CONNER, of Cleveland, in the county of Cuyahoga and State of Ohio, have invented a new and original Design for Pad-Hooks, of which the following is a full, clear, and exact description, reference being had to the accompanying drawing, forming part of this specification, which shows in perspective view a pad-hook embodying my design.

The design consists in a pad-hook having the form and outline substantially as herein shown and described.

In the drawing, 2 represents the body or shank of the pad-hook; 3, the hook-shaped portion; 4, a pin having a head 4', which projects from the shank; 5, a loop at the rear end, and 6 a projecting cross-rib.

I claim—

The design for pad-hooks, substantially as herein shown and described.

In testimony whereof I have hereunto set my hand.

FLORENCE F. CONNER.
